UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT MOLDS.

Application filed November 1, 1924. Serial No. 747,323.

To all whom it may concern:

Be it known that we, BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Feeders for Ingot Molds, of which the following 10 is a specification.

Our invention relates to improvements in feeders for ingot molds used in the manufacture of iron or steel ingots and has for its object the prevention of holes or seams 15 in the upper end of the ingot known as "piping" and at the same time produce a feeder which will reduce segregation to a minimum.

Another object of our invention is to provide a feeder made of refractory material 20 and having a metal strengthening means extending around a portion of the feeder above the mold, and at the same time provide means whereby this metal strengthening 25 means may be readily placed on the refractory feeder so that it can be removed and used on other refractory feeders; also to provide a reversible feeder.

A further object of our invention is to 30 provide a feeder of this character in which the metal strengthening means serves as a support for the feeder within the upper end of the ingot mold.

A still further object of our invention is 35 to provide a simple, cheap and effective feeder of this character having certain details of structure and combination of parts hereinafter more fully pointed out.

In the accompanying drawings:

40 Figure 1 is a perspective view of an ingot mold showing our improved feeder applied thereto.

Figure 2 is a transverse vertical sectional view of Figure 1.

45 Figure 3 is a top plan view of a circular mold and feeder employing the same principle as that shown in Figures 1 and 2.

Figure 4 is a transverse vertical sectional view of a modified form of feeder.

50 Figure 5 is a top plan view of Figure 4.

Figure 6 is a top plan view of a circular mold and feeder employing the same form as that shown in Figures 4 and 5.

Figure 7 is a transverse vertical sectional

view of a still further modified form of 55 feeder.

Figure 8 is a top plan view of Figure 7.

Figure 9 is a perspective view of a circular mold showing a fluted refractory feeder having the metal supporting and strength- 60ening band applied thereto:

Figure 10 is a transverse vertical sectional view of a modified form employing the principle shown in Figure 4 of the drawings.

Figure 11 is a top plan view of a modified 65 form of the principle involved in Figure 10.

Figure 12 is a transverse vertical sectional view of a still further modified form.

Referring now to the drawings, 1 represents the mold and 2 the refractory feeder, 70 which as shown, is made of tubular form and of a contour to correspond with the bore 3 of the mold. This feeder of refractory material may be made round, square or any 75 desired shape to fit any form of mold, as the shape thereof forms no part of this invention. The upper and lower ends of the refractory feeder are beveled as indicated at 4 and 5, and surrounding the upper end of the refractory feeder is a metal supporting and strengthening band 6. This band as shown in Figure 2 of the drawings, has its interior bore slightly tapering so that it can be forced on the feeder 2 and frictionally held.

80 From the foregoing description it will be seen that we have produced a feeder of refractory material, the upper end above the mold being strengthened by the metal band 6 and which also serves as supporting means for holding the refractory feeder within the upper end of the mold. From Figure 2 of the drawings it will be seen that the exterior diameter of the refractory feeder 2 is the same or slightly less than the bore 3 of the 85 mold 1, in order to allow it to freely pass within the bore of the mold. By this structure it will be seen that after the feeder has been used in casting the ingot, the metal band 6 can be removed and placed upon another refractory feeder. It is of course understood that refractory feeders for ingot molds are never used more than once, but by making the band 6 so that it can be readily placed upon the feeder the band can be 100 105 used over and over again.

In Figure 3, the feeder 1 is of a circular form and the refractory feeder 7 of a cor-

responding form, and the band 8 arranged to closely fit the exterior diameter of the refractory feeder and frictionally held thereon in the same manner as that described 5 in respect to Figures 1 and 2.

In Figure 4, the mold 1 is constructed the same as that shown in Figures 1 and 2, and the metal band 9 has its interior bore 10 at its upper end of a diameter greater than the 10 bore 11 of the mold, and the interior bore of the metal band 9 is tapered inwardly as indicated at 12 so that its lower end is of the same diameter as that of the bore 11 of the mold. The feeder 13 is of a cylindrical form 15 and made of refractory material and has its exterior diameter at its upper end tapered outwardly as indicated at 14 to correspond with the taper 12 of the band 9 whereby the feeder 13 is supported by the taper 12 of 20 the band 9 and the band 9 is supported upon the upper edge of the mold.

By the structure described in respect to Figure 4 it will be seen that the refractory feeder 13 is readily placed within the metal 25 band 9 and supported thereby and can be readily removed for the insertion of a new refractory feeder.

In Figure 6, the band 15 is made of circular form to correspond with the circular bore of the mold 1 and the refractory feeder 16 is made circular and the same principle is employed for supporting the feeder in the band as that shown in Figure 4.

Referring now to Figures 7 and 8, the refractory feeder 17 has its interior bore of the same diameter throughout its length and its exterior diameter gradually increasing from its lower end 18 to its upper end 19. This makes the exterior diameter of the 35 lower end of the feeder slightly less than the diameter 20 of the bore of the mold 1. The band 21 has its interior diameter slightly tapered as indicated at 22 whereby the band can be readily slipped on the lower 40 end of the feeder 17 and forced upwardly to the position shown in Figure 7 where it is tightly held upon the feeder and strengthens that portion of the feeder above the mold, and also forms means for supporting the 45 feeder within the upper end of the mold.

In Figure 9 the same principle is applied, but a fluted feeder 23 is employed having the tapered outer diameter, and the band 24 has the tapering fluted inner diameter whereby the band is wedged upon the feeder the same 55 as that shown in Figure 7.

In Figure 10 we have shown the band 25 having an interior bore 26 of a diameter considerably greater than the bore 27 of the 60 mold 1, and provided at its lower end with an inwardly extending flange 28, the inner edge of which extends in close to the bore 27 of the mold 1. The feeder 29 is of refractory material and of an exterior diameter to closely fit the bore 27 of the mold. 65

The upper end of the feeder 29 is provided with an outwardly extending annular flange 30 adapted to rest upon the upper face of the flange 28 carried by the band 25, whereby the feeder is supported within the upper end 70 of the mold and can be readily removed from the band.

In the modification shown in Figure 11 we have employed the same principle as that shown in Figure 10 except that the 75 feeder 31 is provided with four outwardly extending lugs 32 instead of the flange 30 adapted to rest upon the flange 28 of the band 25.

In the modification shown in Figure 12, the feeder 33 is of an elongated form and slightly tapered from its upper end 34 to its lower end 35 and the band 36 has its interior wall 37 slightly tapered whereby the band is tightly wedged upon the feeder 33, at a point between its ends so that the feeder can be reversed in the mold 1 and supported by the band when either end of the feeder is within the mold.

Having thus fully described our invention 90 what we claim is:—

1. A feeder for ingot molds comprising a body portion of refractory material, and a band around only the upper end of the feeder for strengthening the same and supporting it within the upper end of the mold. 95

2. A feeder for ingot molds comprising a body portion of refractory material, and a broad metal band around only the upper end of the feeder for strengthening the same 100 and supporting it on the upper end of the mold.

3. A feeder for ingot molds comprising a body portion of refractory material, and a metal band around only the upper end of the same for strengthening the same and supporting it in the upper end of the mold. 105

4. A feeder for ingot molds comprising a body portion of refractory material having an exterior diameter less than the bore of the mold, and a metal band around only the upper end of the same and supporting it in the upper end of the mold. 110

5. A feeder for ingot molds comprising a body portion of refractory material, and a metal band around only the upper end of the same and frictionally held thereon and adapted to strengthen the same and supporting the refractory body portion in the upper end of the mold. 115

6. A feeder for ingot molds comprising a body portion of refractory material, and a removable metal band held on only the upper end of the feeder for strengthening and supporting the feeder within the upper end of the mold. 120

7. A feeder for ingot molds comprising a body portion of refractory material having tapering outer walls, and a band only on the upper end of the feeder for strengthening 125 130

the same and supporting it on the upper end of the mold.

8. A feeder for ingot molds comprising a body portion of refractory material having its outer wall of the upper end enlarged and a metal band only on the upper end of the feeder having a reduced lower end to engage

the enlarged upper end of the feeder for strengthening the same and supporting it on the upper end of the mold.

In testimony whereof we affix our signatures.

BLOOMFIELD H. HOWARD.
ERNEST J. TURNER.
